UNITED STATES PATENT OFFICE.

AKSEL R. THOMPSON, OF NEW YORK, N. Y., ASSIGNOR TO THE BRUNSWICK-BALKE-COLLENDER COMPANY, OF CHICAGO, ILLINOIS, A CORPORATION OF DELAWARE.

BOWLING-ALLEY PIN SPOTTER.

Application filed August 9, 1926. Serial No. 128,131.

This invention relates to bowling alley pin spotters of that type which comprises a plurality of pegs movably arranged in the alley bed to engage the bottoms of the bowling pins. The pegs have been supported upon a movable frame arranged beneath the alley bed and adapted to be operated by a pin-boy to move the pegs up through openings in the bed to receive the bowling pins and to lower the pegs or to permit the pegs to lower below the surface of the alley bed after the bowling pins have been properly spotted.

My invention has for its object to provide simple means for engaging the pegs with the frame whereby it is possible to effect this engagement after the frame has been installed beneath the alley bed and wholly through the spot openings in the bed.

And a further object of the invention is to provide a novel and effective manner and means for engaging the peg with the frame whereby the peg will be raised and lowered by operating the frame.

In the accompanying drawings illustrating selected embodiments of the invention:

Fig. 1 is a sectional view through the pin end of a bowling alley bed and the spotter associated therewith.

Fig. 2 is a bottom plan view of the pin end of the alley bed showing the spotter.

Fig. 3 is a detail sectional view showing the manner in which a peg is engaged with the frame.

Fig. 4 is a detail sectional view through a pin spot and showing also the bottom of a bowling pin.

Fig. 5 is a detail plan view of the pin spot opening in the alley bed.

Referring to the drawings 6 is the alley bed of suitable construction and 7 is the spotter frame which is conveniently made of angle iron in triangular shape. A lever 8 is pivoted between its ends at 9 to a bracket 10 on the under side of the bed, and the front end of this lever is pivoted at 11 to the frame and the rear end of the lever projects at the rear end of the alley bed and is provided with a foot piece 12 whereby the lever may be operated by the pin-boy to raise the frame. The weight of the frame and the parts carried thereby is sufficient to lower the frame when the pin-boy removes his foot from the foot piece 12. Straps 13 are fastened to the bed 6 and form guides

for the corners of the frame in its vertical movements.

The alley bed is provided with an opening 14 extending therethrough for each bowling pin and a pin spot is secured in this opening. One form of pin spot is made of metal or other suitable material and comprises a tubular sleeve 15 having an annular flange 16. The sleeve fits in the opening 14 in the alley bed and the flange 16 seats in the recess 14' in the top of the alley bed. Screws 17 passing through the flange secure the spot to the alley bed with the top of the spot flush with the top of the bed (Fig. 4). A peg 18 is arranged in each pin spot and opening and is engaged at its lower end with the frame. The pegs are of sufficient length so that when the frame is in elevated position they are projected above the surface of the alley bed sufficiently to engage openings 19 in the bottom of the bowling pins 20, and when the frame is in lowered position the top of the pins will be below the surface of the alley bed.

My invention has to do primarily with the construction of the peg and the manner and means of engaging the peg with the frame. I provide the peg with a hook 21 at its bottom which is arranged to pass through an opening 22 in the frame. The hook constitutes a reduced end for the peg and provides a shoulder 23 on the peg which rests upon the frame. Of course the opening 22 in the frame will be of less size than that of the peg at the shoulder so that the peg will not drop through the frame; and the opening will also be of such a size as will not permit the disengagement of the peg from the frame while the peg is in vertical position. The form of the hook is that of a laterally bent reduced lower end of the peg. To permit the peg to be engaged with the frame after the frame has been installed, I provide a recess 24 in the bed at one side of the opening 14 therein, this recess being inclined and of sufficient size to receive the peg in inclined position as shown in Fig. 3.

From this it will be readily understood that the peg is engaged with the frame before the pin spot is arranged in place in the alley bed. The peg is arranged in the opening 14 and recess 24 so that the hook end 21 will engage the opening 22 in the frame 7 when the latter is in elevated position. Then the peg is moved to upright position, the

pin spot is secured in place and thereafter the peg will rest squarely upon the frame and the pin spot sleeve will cover the recess 24 and the pin spot will form a guide for the peg to hold it in upright position. Whenever it becomes necessary to replace a peg the pin spot will first be removed and then the peg will be tilted into the recess 24 and withdrawn from engagement with 10 the frame. This enables the replacement of a peg at any time by any person and with very little interruption to the game; it requires the use only of a screw driver to remove and replace the screws 17, and it 15 can be accomplished quickly without loosening or removing any other parts.

I do not limit the invention to use with the particular frame and pin spot and other parts herein shown and described but I reserve the right to make all changes in the form, construction and arrangement of the invention and to embody the same in any pin spotter for which it is or may be adapted, within the scope of the following claims:

25 I claim:

1. A peg for a bowling alley pin spotter having a laterally bent end to permit detachable engagement with the spotter frame.
2. A peg for a bowling alley pin spotter 30 having a laterally bent end to permit detachable engagement with the spotter frame and a shoulder above said end to engage the frame.
3. A peg for a bowling alley pin spotter 35 having a reduced laterally bent end to permit detachable engagement with the spotter frame.
4. A peg for a bowling alley pin spotter 40 having a reduced laterally bent end to permit detachable engagement with the spotter

frame and a shoulder above said end to engage the frame.

5. The combination of a bowling alley pin spotter comprising a frame having an opening therein, and a peg having a laterally bent end adapted to be engaged with said opening by tilting the peg relative to the frame and then uprighting the peg.

6. The combination of a bowling alley bed having an opening therein, a movable frame 50 beneath the bed and having an opening therein, and a peg having a laterally bent end adapted to enter the opening in the frame when the peg is arranged in an inclined position in the opening in the bed 55 and adapted to be engaged with the opening in the frame when the peg is arranged in upright position in the opening in the bed.

7. The combination of a bowling alley bed having an opening therein, a frame movable 60 beneath the bed and having an opening therein, a peg having a laterally bent end adapted to be engaged with the opening in the frame, and a pin spot adapted to be secured in the opening in the bed to maintain 65 the peg in upright position and in engagement with the frame.

8. The combination of a bowling alley bed having an opening therein and a recess at one side of said opening, a frame having an 70 opening therein, and a peg having a laterally bent end adapted to enter the opening in the frame when the peg is arranged in inclined position in the opening and the recess in the bed and adapted to be engaged 75 with said opening in the frame when said peg is arranged in upright position in the opening in the bed.

AKSEL R. THOMPSON.
